UNITED STATES PATENT OFFICE

EDWARD FLYNN, OF TIFFIN, OHIO

RADIATOR

Application filed March 23, 1929. Serial No. 349,463.

This invention relates to new and useful improvements in radiators and more especially to a device or mechanism for regulating the steam or vapor supply to a radiator connected to a one pipe steam heating system.

The primary object of my invention is to provide a valve that can be opened in order to heat all or any part of a radiator and at the same time allow the water of condensation to flow out of the radiator freely, and which valve will close automatically when the steam supply is turned off, or the supply fails for any reason.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a side elevation, partly in section, illustrating the application of my invention, the drip valve closed, and Figure 2 is a vertical section, the drip valve open.

Referring to the drawings for a more particular description of my invention and in which drawings like parts are designated by like reference characters throughout the several views, 1 designates the radiator, 2 the steam supply pipe, 3 an elbow at the upper end of the steam supply pipe, 4 the steam valve and 5 the connection between the elbow 3 and the radiator. In carrying out my invention, a thermostatic valve or disc 6 is mounted in the connection 5 and is carried by the upper end of the vertical rod or plunger 6'. The rod or plunger is preferably made in a number of sections 7 and works through the stuffing boxes 8 and 9.

The lower end of the rod or plunger carries the removable disc-shaped valve 10, adapted to close the valve opening 11 in the valve casing 12 when the steam valve 4 is closed and the steam supply accordingly cut off. The valve 10 is normally held closed or seated

by the coil spring 13 in the bottom of the valve casing 12. The valve casing is connected with the radiator and steam supply pipe by the horizontal tubes or pipes 14 and 15, respectively.

In practice, the opening of the steam valve 4 expands the thermostatic valve or disc 6 and thus opens the drip valve 10 against the tension of the coil spring 13. Closing of the steam valve cools the thermostatic valve or disc, thereby causing it to contract and permitting the coil spring to again function to close the drip valve. It will be understood that when the drip valve is open, the water of condensation from the radiator is returned to the steam supply pipe and that the drip valve remains closed until opened by the heating of the thermostatic valve or disc. The purpose of my invention is to provide an arrangement that will operate to heat a radiator and at the same time allow water of condensation to flow out of the radiator freely and the drip valve close automatically when the steam supply is turned off, or fails from any cause. With the devices and appliances now in use, the steam valves on a radiator connected with a one pipe system must be entirely opened or closed or condensation of the steam or vapor will fill the radiator and result in the cooling of the radiator, thus holding water from the boiler, which should return to it, and causing knocking in the heating system. My device, because of its thermostatic control, will cause the steam to enter through, and condensation to leave through, separate openings in the radiator, and the above mentioned trouble is avoided, and partial or complete heating of the radiator is attained, if desired, by hand operation of the steam valve.

From the foregoing description taken in connection with the drawings, it is thought that the construction, operation and advantages of my invention will be readily understood without requiring a more extended explanation.

Having described my invention, what I claim as new and desire to secure by Letters Patent, is:

In a device of the character specified, a

radiator, a steam supply pipe for the radiator, a return pipe therefor, a steam valve in the supply pipe, a spring closed drip valve in the return pipe, a thermostatic element 5 acting to expand and open said drip valve against the action of its spring when the steam valve is opened and contracting to permit the drip valve to close again when the steam supply is shut off and a vertical 10 rod or plunger between the thermostatic element and drip valve.

In testimony whereof he affixes his signature.

EDWARD FLYNN.
